CLAIM

The ornamental design for a camera mount for collapsible camera crane, as shown and described.

DESCRIPTION

FIG. 1 is a perspective view of a camera mount for collapsible camera crane, with the collapsible camera crane in a collapsed configuration;

FIG. 2 is a rear elevation view of FIG. 1;

FIG. 3 is a front elevation view of FIG. 1;

FIG. 4 is a left-side elevation view of FIG. 1;

FIG. 5 is a right-side elevation view of FIG. 1;

FIG. 6 is a top plan view of FIG. 1;

FIG. 7 is a bottom plan view of FIG. 1;

FIG. 8 is a perspective view of the camera mount for collapsible camera crane, with the collapsible camera crane in an extended configuration;

FIG. 9 is a rear elevation view of FIG. 8;

FIG. 10 is a front elevation view of FIG. 8;

FIG. 11 is a left-side elevation view of FIG. 8;

FIG. 12 is a right-side elevation view of FIG. 8;

FIG. 13 is a top plan view of FIG. 8; and,

FIG. 14 is a bottom plan view of FIG. 8.

The broken lines shown in the drawings depict portions of the camera mount for collapsible camera crane that forms no part of the claimed design.
